COMBINATION RECEPTACLE FOR
REFRIGERATORS

Alvis Yates Dowell, Hastings-on-Hudson, N. Y.,
assignor to Servel, Inc., New York, N. Y., a cor-
poration of Delaware

Application October 1, 1932, Serial No. 635,753

12 Claims. (Cl. 62—141)

This invention relates to receptacles for use in refrigerators and more particularly to a receptacle adapted to separately contain a plurality of substances.

5 In mechanical refrigerators in which the cooling element is maintained at a temperature low enough for rapid freezing of water into ice cubes and is also utilized for cooling the air in a storage compartment, there is continuous condensation 10 of moisture out of the air onto the cooling element due to its low temperature. The condensate freezes and as a result the cooling element becomes covered with a gradually thickening coat of frost which for sanitary reasons and also 15 for efficiency of operation should be intermittently removed. This is usually accomplished by raising the temperature of the cooling element to melt the frost, commonly referred to as defrosting, and a receptacle usually in the form of a 20 pan or tray is provided beneath the cooling element to receive the drip during the defrosting period.

This invention contemplates a drip pan having a segregated compartment for containing drinking water or other substance to be cooled in the refrigerator. Obviously, however, the invention is not so limited but a combination receptacle contemplated by this invention may be utilized for the reception of any plurality of substances 30 desired to be separately contained in a refrigerator.

The invention will be more fully understood by reference to the following description taken in connection with the accompanying drawing, in 35 which,

Fig. 1 shows in perspective a mechanical refrigerator provided with a combination "defrosting" pan and drinking water reservoir in accordance with the invention;

40 Fig. 2, an enlarged perspective of the combination receptacle shown in Fig. 1; and

Figs. 3 and 4, vertical sections showing the construction of two embodiments of the invention.

Referring to Figs. 2 and 3 of the drawing, a pan 45 or receptacle 10 is provided with a horizontal partition 11 forming an upper chamber 12 open at the top and a lower fluid tight chamber 13. The partition 11 is provided with an upstanding portion or boss 14 having an opening adapted to 50 be closed by a screw plug 15 or other suitable closure member. A gasket or washer 16 is provided between the plug 15 and boss 14 to insure a tight closure.

At one end of the receptacle 10 there is provided a tap or faucet 17 of the push valve or

other desired type for withdrawing liquid from the lower compartment 13. With this construction there results a unitary structure having a closed lower compartment and an upper compartment open at the top. The upper compartment is in the form of a trap for the reception of drip from the cooling element 18 when the combination receptacle is located in the refrigerator 19 where it is supported by a shelf 20 in the refrigerator storage compartment immediately below the cooling element as shown in Fig. 1. The closed compartment 13 may be filled with drinking water or other liquid through the opening in boss 14 and the water withdrawn for use as desired through the faucet 17. When the receptacle is located in the refrigerator as shown in Fig. 1 the liquid in the lower compartment is cooled both by radiation and convection from the cooling element 18 and also by conduction through the partition which separates the compartments 20 when the upper receptacle contains liquid cooler than the liquid in the lower compartment as during defrosting.

As shown in Fig. 4 of the drawing the combination receptacle may be constructed by nesting two 25 pans of different depths. The outer pan 21 may be similar to the container 10 shown in Fig. 3 and provided with a faucet 22 in the lower part thereof in the same manner. A shallow pan or tray 23 is provided with an overturned rim 24 and 30 nested within the pan 21 with the overturned rim resting on the upper edge of the deeper pan. The two pans 21 and 22 may be permanently secured together in this position or the shallow pan or tray 23 made removable thus allowing greater 35 flexibility in the use of the device.

In the use of the receptacle described above, the tray 23 collects and retains drip from the cooling element during the defrosting interval and the lower compartment 25 formed in the 40 lower part of the pan 21 may be used to store drinking water or other liquid. To facilitate filling the liquid compartment 25 without removal of the tray 23 the bottom of the latter is provided with an upturned portion or boss 26 having an 45 opening closed by a screw plug or other suitable closure member 27. I prefer to provide the filling opening for the lower compartment in an upturned portion 26 of the tray 23 thereby bringing the opening above the level of liquid contained in the tray thus obviating any seepage past the closure member 27 into the lower compartment.

It will be obvious that various other changes and modifications may be made in the construc- 55

tion and arrangement without departing from the spirit of the invention and therefore the invention is not limited to what is shown in the drawing and described in the specification but only as indicated in the appended claims.

I claim:

1. A receptacle having a plurality of compartments, one of said compartments being completely closed and provided with a portion extending through another compartment defining a filling opening, a closure member for said opening, and a faucet for withdrawing liquid from said compartment, both of said compartments being constructed to contain a substantial body of liquid whereby heat transfer is provided between liquid contained in said compartment having the filling opening extending therethrough and another compartment.
2. A receptacle having an upper compartment open at the top and a closed lower compartment having a portion extending through the upper compartment and defining a filling opening, a closure member for said opening, and a faucet for withdrawing liquid from said lower compartment, said upper compartment being constructed to contain a substantial body of liquid whereby interchange of heat between said compartment and an adjacent compartment is effected.
3. A receptacle comprising a pan, a horizontal partition in said pan between the bottom and rim thereof having a portion extending through said pan and defining an opening through said partition, closure means for said opening, and a faucet on said pan below said partition, said partition defining an upper compartment of a depth to retain a substantial body of liquid and a lower compartment whereby heat exchange is effected between liquids in said compartments.
4. A receptacle comprising a pan, a tray nested in said pan to form a closed compartment in the lower part of the latter, and a faucet on said pan for withdrawing liquid from said compartment, said tray being constructed to contain a substantial body of liquid whereby heat exchange is effected between liquid in the tray and said closed compartment.
5. A receptacle comprising a pan, a tray having an opening in the bottom thereof and adapted to be nested in said pan to form a closed chamber in the bottom thereof, closure means for said opening, and a faucet on said pan for withdrawing liquid from said chamber, said tray being constructed to contain a substantial body of liquid whereby heat exchange is effected between liquid in the tray and said closed compartment.
6. A receptacle comprising a rectangular pan, a rectangular tray having an outwardly extending rim adapted to be supported in the upper part of said pan by said rim on the upper edge of the pan, and a faucet on the lower part of one end of said pan, said tray being constructed to contain a substantial body of liquid whereby heat exchange is effected between liquid in the tray and said closed compartment.
7. A combination defrosting pan and reservoir

for drinking water comprising a closed lower receptacle and an open upper receptacle constructed to contain a substantial body of liquid whereby heat exchange between said receptacles is effected, said receptacles forming a unitary structure, the closed lower receptacle having a portion extending upwardly through and to the plane of the top of the open upper receptacle and providing a filling opening for the lower receptacle.

8. A combination defrosting pan and reservoir for drinking water comprising a closed lower receptacle and an open upper receptacle constructed to contain a substantial body of liquid whereby heat exchange between said receptacle is effected, said receptacles forming a unitary structure, the closed lower receptacle having a portion extending upwardly through and to the plane of the top of the open upper receptacle and providing a filling opening for the lower receptacle, and means for discharging liquid from said lower receptacle.

9. A receptacle comprising a pan, a tray nested in said pan for containing a substantial body of liquid for cooling the pan, said pan and tray forming a closed compartment beneath the tray in the lower part of the pan, and an open compartment above the tray in the upper portion of the pan, and means whereby access may be had to the interior of the compartment beneath the tray through the tray, which means is constructed to exclude liquid contained in the tray from running into the lower compartment.

10. A combination receptacle comprising partition means defining a plurality of compartments, said partition having a rim for retaining a substantial body of liquid upon said partition and also having a portion defining an opening and constructed to exclude liquid passing by gravity through said partition.

11. A combination defrosting pan and reservoir for drinking water comprising a closed lower receptacle for water to be cooled, an open upper receptacle for collecting a substantial body of water discharged from the evaporator of a household refrigerator, means for discharging water from the lower receptacle, the lower receptacle having a portion extending upwardly through the upper receptacle and defining a filling opening for the lower receptacle, and a closure for said opening extending above the top of the upper receptacle permitting removal of said closure without contact with the liquid in said upper receptacle.

12. A combination defrosting pan and reservoir for liquid to be cooled comprising a pan having a partition disposed within the pan parallel to its bottom and provided with an upstanding portion defining a filling opening with a reservoir about the filling opening for defrosting water from the cooling unit of a mechanical refrigerator, the construction being such that the defrosting water is adapted to cool the water within the lower portion of the pan.

ALVIS YATES DOWELL.
